UNITED STATES PATENT OFFICE.

ELMER A. KLAPP, OF NEW YORK, N. Y.

DESIGN FOR AN EMBLEM, BANNER, OR ARMBAND.

55,798.

Specification for Design.

Patented July 13, 1920.

Application filed March 4, 1918. Serial No. 220,401. Term of patent 3½ years.

To all whom it may concern:

Be it known that I, ELMER A. KLAPP, a citizen of the United States, residing at New York, in the county of New York and State of New York, have invented a new, original, and ornamental Design for an Emblem, Banner, or Armband, of which the following is a specification, reference being had to the accompanying drawings, forming part thereof.

The design shown includes red and blue stripes over-laid with a five pointed star in white, the three colors constituting the national colors, and the whole being surrounded by a black band or border indicating mourning for the lost hero.

The figure is a view of an emblem, banner or arm-band showing my new design.

I claim:

The ornamental design for an emblem, banner, or armband as shown.

ELMER A. KLAPP.
